UNITED STATES PATENT OFFICE

WALLACE D. SMITH, OF NEW BRITAIN, CONNECTICUT

GOLF-TEE RETRIEVER

Application filed April 15, 1929. Serial No. 355,133.

My invention relates to improvements in golf tee retrievers and the combination therewith of a tee of novel form made of a piece of wire and securely fastened to the flat tape-like flexible element of the retriever, and the object of my improvement is to produce a retriever structure that is provided with a ratchet and pawl checking mechanism that automatically checks return winding of the flexible element after a length thereof has been withdrawn from the casing; that has button-operated release means for said checking mechanism; that has holding means for the casing that cooperate with the shoe and the foot for supporting the retriever; and in which combination the tee besides having a seat for the ball and a stem is provided with a loop or the like for receiving the free end of the flexible element.

20 In the accompanying drawing:—

Figure 1 is a plan view of my improved golf tee retriever combination, the retriever being shown in position on a shoe, and the arms on the casing that are positioned for support between the foot and the side wings or flaps of the shoe indicated by broken lines.

Figure 2 is a sectional view on an enlarged scale of the retriever through the middle thereof.

30 Figure 3 is a bottom face view of the retriever, with the casing bottom removed.

Figure 4 is a top view of the retriever, with part of the top wall broken away so as to expose parts of the spring, drum, and flexible element.

Figure 5 shows part of a shoe as in Fig. 1 and indicating by broken lines the outline of the casing for the retriever and the supporting arms of the clip structure.

40 Figure 6 is a side view of the wire-formed tee.

My improved golf tee retriever comprises as the operating elements a flexible member 10 that is connected by its free end with the tee 11; a casing 12 in which is housed the mechanism for withdrawing the major portion of said flexible member 10 within itself involving a coil spring 13 and a drum 14 and a ratchet device for checking the operation of said spring; and a button or trigger 15.

The elements of the operating mechanism enumerated correspond substantially in their arrangement and operation to devices that are in the form of tape measures with spring operated mechanism and casings, but no tape measure device or structure known to me will suffice or is adapted for use as a tee retriever and operate satisfactorily or reliably for several reasons.

For instance, the work for the spring in such a tape measure device is confined to withdrawing and winding the tape, which corresponds to the flexible member in the present structure whereas in the retriever there is the tee to be carried.

Not only is the weight of the tee a factor that is appreciable as an ordinary proposition, but the action in retrieving is most satisfactory when the coiling upon pressing the button is exceptionally quick and so as to be suggestive of instantaneous action.

To meet this last named condition an exceptionally powerful spring 16 is provided.

The inner end 17 of said spring 16 is connected to some part of a barrel structure 18 at the middle of the casing 12 and that serves as a guide-housing for the cylindrical body portion 19 of the structure of the button 15.

The outer end 20 of the spring 16 is connected to the tape-supporting cylindrical wall 21 of the drum 14.

The ratchet teeth 22 are provided on the disc-like rear or bottom wall 23 of the drum 14 and these cooperate with a pair of arms that serve as pawls and are provided on the structure of the button 15. Said button 15 is backed by a diminutive coil spring 25.

The body portion 19 supports the pawl arms 24 at the bottom end and at the top end merges with the rounded contact end 26. Said contact end 26 is exposed and accessible through an opening 27 in the top wall 28 of the casing 12.

The supporting means for the casing 12 comprises a clip structure 29 that is mounted 95 securely upon the outer face of the bottom wall 30, preferably at the center thereof, and is provided with a pair of supporting arms 31 of appreciable length that extend outwardly in diametral alignment from the central hub 100.

or junction 33 and that are spaced from the opposed face of said bottom wall 30. The space 34 between these parts corresponds substantially to the thickness of the leather of the side wings 35 of a shoe 36 and the thickness of the junction structure or hub 33 is such as to be admitted freely and in many cases to fit snugly between the opposed edges 37 of said wings 35 after the shoe has been secured on the foot by means of the lacings 38.

The structure described permits of utilizing the shoe lacings in cooperation with the foot for holding the casing 12 in place suitable for use in cooperation with the tee 11.

Thus means are provided for retrieving the tee by the use of a golf-club as the trigger or button operating device. The casing 12 is made so as to permit of such use.

An important element in facilitating efficient operation is that of the flexible element 10, which in the present instance is in the form of a flat strip that emerges from the casing 12 through a narrow slot, after the manner of tape measures mentioned.

The material of the flexible member or tape structure 16 is of substantial quality, of special fabric and treated to stand exposure to the elements.

In use, the tape is pulled from the casing to the desired amount with a little extra for slack while the tee is in position for use and after use the tee is pulled to the side of the casing 12 by pressing the button in any manner that may be convenient.

The use of a flexible connecting member 10 in the form of a tape that emerges from the casing through a narrow slot 39 and that winds on the drum compactly in layers is believed to be new in a golf tee retriever.

The free end of the flexible member 10 is secured to the tee 11 in any manner so as to provide a relatively positive and reliable connection so that the tee will be released from its position in the ground if necessary and in all cases will be moved with the shoe to which it is connected. This condition permits of the introduction of another desired improvement, involving the material used for the tee itself, which is the use of metal.

There is valid objection to the use of tees of metal on a course that is gone over by a grass cutter of any kind, as is usual, when there is involved a liability or probability that an appreciable percentage thereof will be left on the course and in the path of the cutter.

In the tee 11 I have provided a form of structure that overcomes this objection in combination with the retriever as described.

The said tee 11 is made of a single piece of wire. One end portion of said wire is bent to form the upper end part 40 of the tee structure, which is in the form of a circular

seat for receiving the golf ball and the other end portion 41 constitutes the stem which is downwardly directed and located in line with the axis of said seat 40.

In some cases the extreme tip end of the wire that forms the seat 40 may be bent, as shown, to form a terminal loop 44 to which the free end of the tape 10 may be positively secured in any way that will provide a good connection.

The intermediate portion 42 of the wire merges with the upper seat part 40 and the lower stem part 41 and is bent to properly position these parts.

I claim as my invention:—

A golf tee retriever combination comprising a casing having a top wall that is provided with an opening, a button exposed through said opening, a flexible element emerging from said casing and having the free end adapted to be connected to a tee, winding mechanism for said flexible element connected to the other end thereof, ratchet elements for checking said winding mechanism subject to be released by pressing said button, means for supporting said casing upon the upper portion of the body of a shoe so as to position said button in convenient position for pressing by means of a golf-club, and said last named means being in the form of a clip structure having arms that are directed along a diameter for being positioned under the wings of a lace-shoe and held in place by the lacings.
